(57) **CLAIM**

The ornamental design for a port replicator, as shown and described.

DESCRIPTION

FIG. 1 is a front, top, and right side perspective view of a port replicator showing our new design according to a first embodiment;

FIG. 2 is a front, bottom, and right side perspective view thereof;

FIG. 3 is a right side elevational view thereof;

FIG. 4 is a left side elevational view thereof;

FIG. 5 is a front side elevational view thereof;

FIG. 6 is rear side elevational view thereof;

FIG. 7 is a top plan view thereof;

FIG. 8 is a bottom plan view thereof;

FIG. 9 is a front, top, and right side perspective view of a port replicator showing our new design according to a second embodiment;

FIG. 10 is a front, bottom, and right side perspective view thereof;

FIG. 11 is a right side elevational view thereof;

FIG. 12 is a left side elevational view thereof;

FIG. 13 is a front side elevational view thereof;

FIG. 14 is rear side elevational view thereof;

FIG. 15 is a top plan view thereof; and,

FIG. 16 is a bottom plan view thereof.

The broken lines in the drawings showing portions of the port replicator are included for the purpose of illustrating environmental structure and form no part of the claimed design.
